UNITED STATES PATENT OFFICE

FREDERICK RATCLIFF, OF NEW BEDFORD, MASSACHUSETTS, ASSIGNOR TO
THE PAIRPOINT MANUFACTURING COMPANY, OF SAME PLACE.

DESIGN FOR A PINCUSHION.

SPECIFICATION forming part of Design No. 22,776, dated September 12, 1893.

Application filed June 21, 1893. Serial No. 478,416. Term of patent 7 years.

To all whom it may concern:

Be it known that I, FREDERICK RATCLIFF, of New Bedford, in the county of Bristol and State of Massachusetts, have invented and produced a new and original Design for a Pincushion, of which the following is a specification, reference being had to the accompanying drawing, showing the same.

The leading feature of my design consists in an egg-shaped shell, a portion of which is broken away and replaced by the surface of a cushion, the edge of the shell being irregular and having a broken and cracked appearance.

15 In the drawing, A is the shell, which is

broken away at a, where it is irregular and has a broken and cracked appearance; and B is the cushion which fills the concavity of the shell, and a portion of which takes the place, so far as external contour is concerned, of that part of the shell which is broken away. The shell A and cushion B are supported on a base D, the cushion resting in the shell.

What I claim is—

The herein described design for a pin cushion, substantially as set forth.

FREDERICK RATCLIFF.
